UNITED STATES PATENT OFFICE.

CHARLES W. GIRSCH, OF NEW YORK, AND CHARLES F. ROEHSLER, OF BROOKLYN, N. Y.

DESIGN FOR A POSTAL-CARD.

SPECIFICATION forming part of Design No. 21,950, dated November 1, 1892.

Application filed September 15, 1892. Serial No. 446,020. Term of patent 3½ years.

To all whom it may concern:

Be it known that we, CHARLES W. GIRSCH, residing at New York, in the county of New York, and CHARLES F. ROEHSLER, residing at Brooklyn, in the county of Kings, State of New York, citizens of the United States, have invented and produced a new and original Design for a Postal-Card, of which the following is a specification, reference being had to the accompanying drawing, showing said design.

The figure of the drawing illustrates the design as applied to the back of a postal-card.

Referring to the accompanying drawing, the design may be described as follows:

15 Along the top of the postal-card and to the right is a three-quarter front perspective view of a long building with a sloping roof and a series of arched windows along the façade, a large arched porch in the middle of the façade, 20 one at the middle of the end portion of the building and at each of the corners. To the left of the building is an artificial pond surrounded by a row of pillars, each supporting a statue. To the left of this, in the upper 25 left-hand corner of the card, is a vignette portrait of Columbus. Beneath this is a picture of a ship of the style used in the fifteenth century, under full sail. The building is in the foreground and the sky in the background, and is placed in the upper right-hand portion 30 of the card. The portrait of Christopher Columbus is placed at the left of the view of the building, in the upper left-hand corner of the card. The ship is shown in perspective floating upon the water, with other ships indicated 35 in the distance, and is placed beneath the portrait of Christopher Columbus at the left-hand end of the card. Around and about the portrait and the representation of the ship is arranged certain scrollwork, a portion of which scroll-work extends out to the right from the upper portion of the portrait, partly over the representation of the building.

Having therefore described our invention, what we claim as new, and desire to protect by 45 Letters Patent, is—

The design for a postal-card, as herein shown and described.

In witness whereof we have hereunto affixed our signatures in the presence of two 50 witnesses.

CHARLES W. GIRSCH.
CHARLES F. ROEHSLER.
